UNITED STATES PATENT OFFICE.

ARTHUR STOCKDALE COSLER, OF NEW YORK, N. Y.

SYSTEM FOR SEPARATING FLUID SUBSTANCES.

1,327,944.

Specification of Letters Patent. Patented Jan. 13, 1920.

Application filed October 5, 1918. Serial No. 257,023.

To all whom it may concern:

Be it known that I, ARTHUR STOCKDALE COSLER, a citizen of the United States of America, and resident of 617 Fifth Avenue 5 Building, in the city of New York, in the State of New York, in the United States of America, have invented certain new and useful Improvements in Systems for Separating Fluid Substances, of which the following is the specification.

The invention relates to improvements in means for separating substances of different specific gravity while in their liquid state as described in the present invention and illustrated in the accompanying drawings that form part of the same.

The invention consists essentially of the novel means employed, whereby the substance in suspension in the heavier liquid is allowed to rise through thin layers of liquid and drawn off from its highest elevation and thus removed from the main body by means of overflows maintained at suitable different levels.

The objects of the invention are to relieve acids and other substances utilized in industrial pursuits from hydrocarbon oils, oleoresinous particles and volatile substances, to accomplish this purpose economically during the process of manufacturing or reclaiming the acid liquors, to increase the efficiency in operation of the sulfite acid liquors in the pulp industry and generally to provide a well developed system of separating substances of lighter weight from those of heavier weight holding said lighter ones in suspension.

In the drawings, Figure 1 is a vertical sectional view of the separating chamber showing a side sectional view of the shelves effecting the separation.

Fig. 2 is a vertical sectional view showing a cross sectional view of the shelves effecting the separation and elevation and the discharge receptacle.

Fig. 3 is a diagrammatic view showing the application of the invention in the production of sulfite acid liquor.

Fig. 4 is a plan view of the separating chamber, discharge receptacle and piping.

Like numerals of reference indicate corresponding parts in each figure.

In describing this invention, its application to the production of acid liquors for use in the sulfite pulp industry will be particularly pointed out in order to more clearly

lead to a correct understanding of its parts and operation, though many other applications of the system can readily be made without materially modifying the salient features herein set forth.

The system in the first place may be said to be dependent upon a chamber, receptacle, tank, vat or other inclosure here shown as a wooden tank 1 intermediately arranged between the acid reclaiming tank 2 and acid storage tank 3 and communicating through the discharge receptacle or selector 4 with the reservoir 5, the latter containing the lighter substance separated, herein designated by the chemical name of its principle constituent part cymene being what is familiarly but improperly known as the "turpentine" of the sulfite acid liquor.

The separation of this substance is desirable because it has an intrinsic value in arts and industries and also because the better the separation of this substance from the acid liquor, the better the latter is for its uses in chemical action on pitch-containing wood from which pulp is produced.

The principle of this invention is to elevate, by the formation of layers of fluid at different stages, substances in suspension and to do this the inclined shelves 6 are preferably used. These shelves each occupy the full cross area of the tank 1, the upper ends 7 joining one side of the said tank and the lower ends 8 the other side of the tank, the other sides of the said tank being denoted by the inlet pipe 9 on the one hand and the outlet pipe 10 on the other hand.

The inlet pipe 9 leads from the acid reclaiming tank 2 to and through the bottom of the tank 1, said pipe 9 extending upwardly through corresponding holes in the shelves 6 and just below each shelf having the discharge openings 11 and preferably closed at its upper extremity above the shelves 6 by the cap 12, though it may be passed through the top of the tank to provide for clearing out.

This pipe 9 intersects the shelves 6 midway of the upward incline of said shelves at one side of the tank 1 and the inflowing acid liquor occupies space between the shelves and the substance or substances of lighter specific gravity rise to the under surface of a shelf and flow under each shelf toward the upper edges of said shelves, where the comparatively long and wide openings 13 permit said lighter substances to join the

lighter substances of the next layer above and any heavy solids held in suspension naturally fall toward the lower sides of said shelves to the arc-shaped openings 14 made 5 at the lower extremities of the said shelves.

The pipe 9 is near to the wall of the tank, but not against said wall, as the discharge openings 11 face the tank wall and not the center of the tank.

10 The outlet pipe 10 is closed at its lower end by the block 16 and at its upper end extends through the side wall of the tank 1, as shown or it may be passed through either end of the tank, for providing for clearing 15 out scale, and enters the discharge receptacle or selector 4.

The pipe 10 is formed with the inlet openings 17 in vertical alinement and facing the wall of the tank 1, each opening 17 being 20 flush with the upper surface of a shelf 6, therefore the acid liquor crossing over from the pipe 9 finds egress through the openings 17 from which it flows into the discharge receptacle 4.

25 Meanwhile, the lighter substance, which is a liquid in a finely divided state, having crept along the various stages to its vertical passage rises and forms a solid layer at the top and is drawn off into the discharge receptacle 4 by means of the overflow pipe 18.

The man hole 19 is shown through the top of the tank and the drain 20 through the bottom to remove the solids or residue dropping from the shelves through the lower 35 openings in the shelves.

The discharge receptacle 4 is partitioned to form the inlet compartment 21 into which the pipe 10 empties, said compartment having at one side the overflow wall 22, and over 40 which the acid flows into the outlet compartment 23. The pipe 18 leads to and empties into the compartment 24 of the receptacle 4, said compartment 24 having at one side the overflow wall 25 and over which the lighter 45 substance flows into the outlet chamber and on into the reservoir, the acid liquor from the outlet compartment 23 flowing into the acid liquor storage tank.

Briefly the operation of the system is as 50 follows:—

The acid liquor from the acid reclaiming tank flows through the pipe 9 and up said pipe in the separating tank or chamber and at each outlet opening under a shelf dis- 55 charges between the under surface of the upper shelf and the top surface of the next shelf below.

The result of this is a distribution of the lighter and heavier elements making up the 60 acid liquor as received in the tank 1, the lighter floating up to the upper openings through the shelves and the acid liquor relieved of the lighter substance spreading over and entering the inlet openings to the 65 pipe 10 and as this pipe leads to the com-

partment 21, the acid liquor finds its way to the acid liquor storage tank.

The lighter substance meanwhile has risen in a vertical column through the openings 13 in the shelves 6 and rises and spreads 70 out in a layer above the acid liquor. A column of lighter substance will always be taller than a column of the heavier liquid from which it is separated exerting the same pressure at plane of division, because of the 75 difference in the specific gravity of the two liquids. For instance if you take a layer of cymene 4 feet deep, said layer at the point of division will exert the same pressure as a column of acid liquor forty or 80 forty-one inches deep.

This difference in levels permits the removal of the acid liquor continuously over the wall 22 and the cymene over the wall 25, which must be considerably higher than 85 the wall 22, in order to account for the difference in height of the columns of cymene and acid liquor of equal hydrostatic pressures and provide for the fluctuation in total depths of liquor in the tank caused by 90 various rates of flow through same.

Various changes may be made in the construction of the several parts to the system, without departing from the spirit of the invention, so long as they are within the scope 95 of the claims following.

What I claim is:—

1. In a system for separating fluid substances, inclined shelves suitably inclosed and supported and adapted to spread the 100 fluid and cause the elevation of the lighter element at the upper ends of the inclinations, a tubular inlet member having discharge openings between said shelves respectively; and a tubular outlet member having 105 inlets flush with the surfaces of the shelves and adapted to relieve the liquid of some of the heavier elements.

2. In a system for separating fluid substances, a tank having a plurality of inclined 110 shelves, each of said shelves having an opening in vertical alinement, and means for feeding the fluid between the several shelves and means between the shelves for discharging the heavier elements, coincidently with 115 the flow of the lighter elements to said openings.

3. In a system for separating fluid substances, a tank having a plurality of inclined shelves, each shelf occupying the complete 120 cross area of the tank and having at the upper end a comparatively wide opening and at the lower end a residue opening, an inclosed feed passage extending upwardly through the shelves and having discharge 125 openings at each shelf, an inclosed discharge passage extending upwardly through the shelves and having inlet openings at each shelf, and a discharge passage for the lighter elements.

4. In a system for separating fluid substances, a tank having inclined shelves across the interior thereof and upper and lower openings through said shelves, an inlet pipe 5 passing through said shelves and having discharge openings under each shelf, a discharge pipe passing through said shelves and beyond said tank and having inlet openings above each shelf flush with the upper 10 surface, and a discharge pipe for the lighter elements.

5. In a system for separating fluid substances, a tank having a plurality of incline parallel shelves, each occupying the 15 cross area of the interior and having an opening at the upper end for the lighter substance and a slot at the lower end for the residue, an inlet pipe passing through the bottom and upwardly through said shelves, 20 said pipe having openings below each shelf, a discharge pipe diametrically opposite to said inlet pipe and having inlet openings flush with the upper surfaces of said shelves, said discharge openings in the inlet pipe 25 and inlet openings in the discharge pipe facing the wall of the tank at a point adjacent thereto, and a discharge pipe for the lighter elements.

6. In a system for separating fluid substances, a production tank, a separating tank 30 connected with said production tank having shelves for the spreading of the fluid substance, a discharge receptacle in proximity with the upper end of said separating tank 35 and partitioned into inlet and outlet cham-

bers for the heavier elements and inlet and outlet chambers for the lighter elements, a pipe connecting the discharge of said separating tank with said discharge receptacle for the passage of the heavier elements, a 40 pipe connecting the separating tank and discharge receptacle for the passage of the lighter elements, a storage tank and a reservoir for the lighter elements.

7. In a system of the class described, a 45 main tank, a storage tank, an intermediate tank having distributing means therewithin adapted to create an upward flow of the lighter elements, a pipe from the main tank forming with a pipe vertically arranged 50 within the intermediate tank and the connections therebetween a siphon for the transfer of liquid from one tank to the other, a discharge receptacle in proximity with the upper end of said separating tank and having inlet and outlet chambers partitioned by walls adapted to allow an overflow, an outlet pipe from said intermediate tank to said discharge receptacle, an inlet pipe to said discharge receptacle for the flow of the 55 lighter elements from said intermediate tank, a pipe from said discharge receptacle to said storage tank, a reservoir, and a pipe connecting said discharge receptacle with said reservoir for the passage of the lighter 60 elements.

Signed at the city of New York, this 24th day of July, 1918.

ARTHUR STOCKDALE COSLER.
